(57) **CLAIM**

We claim the ornamental design for an electronic device, as shown and described.

DESCRIPTION

FIG. 1 is a front perspective view of an electronic device showing our new design according to a first embodiment; FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof;

FIG. 9 is a front perspective view of an electronic device showing our new design according to a second embodiment; FIG. 10 is a front view thereof;

FIG. 11 is a rear view thereof;

FIG. 12 is a left-side view thereof;

FIG. 13 is a right-side view thereof;

FIG. 14 is a top plan view thereof;

FIG. 15 is a bottom plan view thereof;

FIG. 16 is a rear perspective view thereof;

FIG. 17 is a front view of an electronic device showing our new design according to a third embodiment;

FIG. 18 is a front view of an electronic device showing our new design according to a fourth embodiment;

FIG. 19 is a front view of an electronic device showing our new design according to a fifth embodiment;

FIG. 20 is a front view of an electronic device showing our new design according to a sixth embodiment;

FIG. 21 is a front view of an electronic device showing our new design according to a seventh embodiment;

FIG. 22 is a front view of an electronic device showing our new design according to an eighth embodiment;

FIG. 23 is a front view of an electronic device showing our new design according to a ninth embodiment;

FIG. 24 is a front view of an electronic device showing our new design according to a tenth embodiment;

(Continued)

FIG. 25 is a front view of an electronic device showing our new design according to an eleventh embodiment; FIG. 26 is a front perspective view of an electronic device showing our new design according to a twelfth embodiment; FIG. 27 is a front view thereof; FIG. 28 is a rear view thereof; FIG. 29 is a left-side view thereof; FIG. 30 is a right-side view thereof; FIG. 31 is a top plan view thereof; FIG. 32 is a bottom plan view thereof; and, FIG. 33 is a rear perspective view thereof.

The evenly-dashed broken lines in the figures depict portions of the electronic device which form no part of the claimed design.

The dot-dash broken lines in the figures represent boundaries of the claimed design and form no part thereof. The appearance of any portion of the article between the evenly-spaced pairs of dot-dash broken lines forms no part of the claimed design.

The rear, left-side, right-side, top, bottom and rear perspective views of the third through eleventh embodiments of the electronic device depicted in FIGS. 17 through 25 have been omitted because they are exact duplicates of the same views of the electronic device design that are depicted in FIGS. 11 through 16.
